(57) **CLAIM**

The ornamental design for a light fixture, as shown and described.

DESCRIPTION

FIG. 1 is a front elevation view of a light fixture in accordance with my design, illustrating a first adjustable position;

FIG. 2 is another front elevation view of the light fixture in accordance with my design, illustrating a second adjustable position;

FIG. 3 is another front elevation view of the light fixture in accordance with my design, illustrating a third adjustable position;

FIG. 4 is another front elevation view of the light fixture in accordance with my design, illustrating a fourth adjustable position;

FIG. 5 is a side elevation view of the light fixture in accordance with my design, illustrating a fifth adjustable position; and,

FIG. 6 is an opposite side elevation view of the light fixture in accordance with my design, illustrating the fifth adjustable position.

The broken lines showing environmental structure are for illustrative purposes only and form no part of the claimed design.
